UNITED STATES PATENT OFFICE.

ALEXANDER MILLER, OF NEW YORK, N. Y., ASSIGNOR OF ONE-HALF TO
ROBERT DEELEY, OF SAME PLACE.

EVAPORATING APPARATUS.

SPECIFICATION forming part of Letters Patent No. 428,281, dated May 20, 1890.

Application filed July 20, 1888. Serial No. 280,499. (No model.)

To all whom it may concern:

Be it known that I, ALEXANDER MILLER, of the city and county of New York, in the State of New York, have invented a new and 5 useful Improvement in Evaporating Apparatus, of which the following is a specification.

My invention relates in part to all evaporating apparatus in which the evaporating 10 pans are provided with contained heating-belts or steam-chambers, and in part only to apparatus in which a partial vacuum is maintained in the pans.

The improvement will be hereinafter fully 15 described, and its novelty will be pointed out in the claims.

In the drawings, Figure 1 represents a side elevation view of an evaporating apparatus embodying my improvement. Fig. 2 represents a side elevation part sectional view of the same apparatus at right angles to the view given in Fig. 1. Fig. 3 represents a horizontal sectional view of the heating-belt or steam-chamber on line $\alpha - \alpha$ of Fig. 2, in 20 which the heating belt or chamber is divided by a curb or partition into two concentric compartments, circular in outline, of horizontal section. Fig. 4 represents a horizontal sectional view of a modification of the heating-belt represented in Fig. 3, in which the inner or contained compartment is located at one side of the center of the belt.

Like letters of reference indicate similar parts in all the drawings.

35 A is an evaporating-pan, which in this example of my invention is of the variety known as a "vacuum-pan," a partial vacuum being maintained therein when in operation. The shell α is represented of cast-iron lined 40 with a copper lining b . The shell and lining are represented as formed in parts or sections united with horizontal flanged air-tight joints $c - c$. The lining b is preferably of thin metal, and the flanges of its several parts are 45 turned over upon and securely held between the flanges of the cast-iron shell. The object of the copper lining is to protect the cast-iron shell from the corrosive effects of the contained liquid. In the drawings, Fig. 2, only 50 that part of the casing above the heating-belt is represented as having a copper lining; but

such a lining might also be applied to the part below the said belt. To prevent a collapse of the thin metal lining from the expansion of air leaking through the shell or 55 unavoidably left between the shell and the lining, I connect the space between the shell and lining with the condenser in any convenient manner, as by suitable pipes passing into and through the shell. In Fig. 2, $g - g$ 60 represent such pipes, one of which is provided for each belt or section of the lined part of the shell, and communicates through the larger pipe h with the condenser B , thereby maintaining a vacuum between the casing a 65 and lining b equal to that of the interior of the vacuum-pan.

C is the vapor-pipe through which the vapors from the vacuum-pan pass into the condenser B , which may be, and, though not represented in detail, is here supposed to be, what 70 is commonly known as the "dry-vacuum" condenser.

i is the condenser leg-pipe, through which the water of condensation descends to the 75 leg-pipe seal-tank j , whence it passes away to drainage basin or sewer.

$k - k$ are strong lugs projecting from the pan and resting upon the floor-timbers $l - l$ for supporting the pan and attachments. 80

That part of the vacuum-pan represented in the drawings which extends below the heating-surface has the form of an elongated funnel, having at its lower end a leg of considerable length for providing a comparatively cool and quiet body of liquid to facilitate the separation and deposit of the solid precipitate, and terminates at the bottom in a pit or pocket m . 85

$z - z$ are lugs resting upon supporting-timbers $l - l$. 90

2 is a discharge-pipe, through which the contents of the pan can be drawn off.

From the pocket m extends a hollow column n , open at its upper end to the atmosphere and containing the elevating apparatus o , in this example a chain of buckets extending upward. I prefer that this upward extension should be to a level above the surface of the liquid in the pan and below the 95 top of the pan. With a closed evaporating-pan, where the evaporating process is carried 100

on under a pressure in the pan exceeding that of the surrounding atmosphere, a similar hollow column containing the elevating apparatus is employed to prevent the contents of the pan from being forced out by the pressure therein, and the hollow column is therefore for such a pan carried to a considerable height above the top of the pan to overbalance that pressure.

10 The hollow column in this invention is not for the purpose of preventing overflow from the opening at which the discharging-elevator is introduced, but is for the purpose of preventing the air from the surrounding atmosphere from entering the vacuum-pan through said opening and vitiating the vacuum therein. Therefore it is necessary only that the hollow column should in my invention extend to such a height that the column of liquid therein and the pressure of the atmosphere thereon should counterbalance the column of liquid in the pan and the pressure of the vapor in the pan, and it is only in order that there may not be any accidental overflow over the top of the said column in case of the vacuum in the pan being broken that the said column should extend upward to a level somewhat above that to which the liquid rises in the pan, and I have 25 for this reason represented it as extended to such a height.

D is a heating belt or chamber contained within the evaporating-pan, in which steam is employed to evaporate the liquid also contained therein. In this example of my invention the heating-belt D is provided with numerous small tubes d, the extremities of which are expanded into an upper and a lower head-plate. The tubes d converge toward the 35 lower head-plate e and diverge toward the upper head-plate f. The distance between the upper ends of the tubes d being greater than that between the lower ends of the same tubes, the steam or vapor produced by the 40 contact of the liquid with the heated tubes d will pass upward through the body of the liquid above the head-plate f of the belt with greater freedom than if the tubes were parallel one with another. To facilitate the 45 construction of a heating-belt D, in which the tubes d diverge and converge, as above set forth, it is desirable that each tube be perpendicular to both the head-plates at the parts where it meets the same. This I accomplish by giving convexity to both head-plates in the same direction—as, for example, as indicated in Fig. 2—by giving to the 50 plate f the form of a part of the surface of a sphere, and giving to the plate e the form of a corresponding part of the surface of a smaller concentric sphere.

E E E are comparatively large tubes flush with the upper head-plate f, and, like the tubes d, converging toward the lower head-plate. They are secured in a suitable manner, as by flanges, to the head-plates, and extend below the bottom head any required dis-

tance, for the purpose of returning the liquid passing up through the small tubes d down again below the heating-belt, carrying with it 70 the solid matter freed from the liquid by the escape of vapor down a distance below the head into the comparatively quiet and cooler liquid, where it can fall freely into the discharging apparatus. These large tubes E E 75 are preferably placed in the center of the heating-pan and equidistant from that center. The said tubes are preferably tapered, the larger ends being upward.

In this example of my invention the heating-belt is divided into compartments, which may be severally supplied with live or expanded steam independently of each other. The compartments in this example are two in number and are of unequal size or capacity, 80 and the live and expanded steam may be taken into either, according to the comparative quantities of either or both kinds of steam that may be at any time available. The compartments may have any suitable 85 form—as, for example, they may be, as indicated in the drawings, circular in horizontal section—and the compartments may be concentric, as represented in Figs. 2 and 3, or the contained compartment may be at one 90 side of the interior of the other.

p and p' are the curbs or partitions by which the belt or chamber is divided into compartments.

q and q' are the inlet steam-pipes communicating with the contained compartment.

r is an inlet steam-belt, formed in this example by an annular enlargement of the belt or section of the cast-iron casing a, which forms the outer walls of the steam chamber 105 or belt D of the drawings. The steam passes from the inlet-belt r into the heating belt or chamber through numerous slits or openings s s.

F is a heater, through which the cold liquid 110 to be evaporated passes before entering the pan.

t is the cold-liquid-inlet pipe, through which the liquid enters the heater.

u is a pipe by which the same liquid is conducted from the heater into the vacuum-pan.

v is a pipe branching from the vapor-pipe before it enters the condenser to convey a part of the vapor into the heater for the purpose of heating the liquid to a certain degree 120 before it enters the pan.

w is an exhaust-pipe, through which the waters of condensation escape from the heater, and through which by suitable means, as an air-pump F, for example, a partial vacuum 125 is maintained in the heater independently of the pan-vacuum and slightly greater than that vacuum to induce a current through the branch pipe v toward the heater.

z' is a pipe connecting the heating-belt with 130 the heater, and through which the waters of condensation from the heating-belt may pass into the heater, imparting its heat to the liquid therein. The heater is placed at a

level sufficiently below the bottom head of the heating-belt to allow the waters of condensation to flow through the pipe z' . In this example of my invention the pipe z' is provided with a stop-cock z^2 , operated by hand. The stop-cock z^2 may be left slightly open—just open enough to allow the waters of condensation to drain off into the heater, but not enough to allow steam to pass through and vitiate the vacuum in the heater. In practice it will be found convenient to let the stop-cock z^2 remain slightly less open than as above set forth, and when the water accumulates in the heating-belt to open wide the cock z^2 and let the accumulated water run into the heater. After thus discharging the water the stop-cock can be again partially closed and allowed to remain slightly open, as above set forth. To provide for drawing off air that may accumulate within the upper part of the heating-belt, I introduce a pipe g' through the side of the pan into the interior of the heating belt or chamber terminating immediately beneath the highest part of the dome-shaped upper head-plate f and communicating with the interior of the condenser B. In this example, for convenience, the pipe g' enters the lower end of pipe h . The pipe g' is provided with an easily-accessible stop-cock g^2 . By opening the stop-cock g^2 communication may be made and broken at will between the interior of the heating-belt and the condenser, and any air from time to time accumulating under the upper head f may thereby be drawn off into the condenser B; or the cock g^2 may remain very slightly open all the time for the escape of air.

What I claim as my invention, and desire to secure by Letters Patent, is—

1. In a heating-belt for an evaporating-pan, the combination, with the relatively small tubes for the upward passage of the liquid, which tubes converge toward the lower head-plate and diverge toward the upper head-plate, of tubes of much larger diameter secured to the upper and lower head-plates and extending for a distance below the latter to return the liquid that had passed upward through the smaller tubes and discharge the solid matter into the comparatively quiet liquid below, said larger tubes also converging toward their lower ends and diverging toward their upper ends, substantially as specified.

2. A heating-belt for an evaporating-pan, 55 circular in horizontal section, having tubes expanded into an upper and a lower head-plate for the passage of the liquid to be evaporated and divided by a circular concentric curb or partition into two compartments for 60 the reception of steam of different pressures, substantially as herein described and set forth.

3. In an evaporating apparatus, the combination, with a vacuum-pan provided with a 65 vapor-pipe, and means in connection with the vapor-pipe for maintaining a partial vacuum in the pan, of a heater, a branch pipe leading from the vapor-pipe to the heater, apparatus for maintaining in the heater a vacuum 70 slightly greater than that of the vacuum-pan to induce a current from the vapor-pipe to the heater, a pipe for supplying liquid to the heater, and a pipe for conducting liquid from the heater to the vacuum-pan, substantially 75 as set forth.

4. In an evaporating apparatus, the combination, with a vacuum-pan provided with a contained heating-belt for steam, of a heater in which a vacuum slightly greater than that 80 of the pan or its condenser may be maintained to induce a current from the vapor-pipe through the heater, the heater being placed a certain distance below the bottom head of the heating-belt to receive the water 85 of condensation from the belt, a branch pipe from the vapor-pipe between the pan and condenser to convey a part of the vapor into the heater, a passage for conducting the water of condensation from the heating-belt to the 90 heater, and pipes for conducting the liquid to be evaporated into the heater, and from the heater into the evaporating-pan above the heating-belt, and means, substantially as described, for drawing off the water of condensation from the heater, all substantially as 95 described and set forth.

5. In an evaporating apparatus, a vacuum-pan having a shell and a lining, the space between the shell and lining being connected 100 with the condenser by pipes passing into and through the shell for maintaining a vacuum between it and the lining, substantially as herein described and set forth.
